SPLIT MECHANISM

William C. Brown, Dayton, Ohio, assignor to The National Cash Register Company, Dayton, Ohio, a corporation of Maryland

Application August 5, 1946, Serial No. 688,513

17 Claims. (Cl. 235—6)

1

This invention relates to accounting machines and similar business machines and is directed particularly to the totalizers of such machines.

The invention is embodied in machines of the general type shown in the following United States Patents Nos. 1,619,796; 1,747,397; 1,749,960; 1,761,542; and 2,262,258, issued March 1, 1927; February 18, 1930; March 11, 1930; June 3, 1930; and November 11, 1941, respectively, to Bernis M. Shipley; No. 2,175,346, issued October 10, 1939, to Maximilian M. Goldberg; No. 2,141,332, issued December 27, 1938, to Charles H. Arnold; 1,693,279, issued November 27, 1928, to Walter J. Kreider; No. 2,345,839, issued April 4, 1944, to Pascal Spurlino, Mayo A. Goodbar, and Marvin D. Frost; No. 2,351,541, issued June 13, 1944, to Everett H. Placke; No. 2,361,662, issued October 31, 1944, to Pascal Spurlino and Conrad Rauch; and No. 2,373,510, issued April 10, 1945, to Pascal Spurlino, Everett H. Placke, Willis B. Eickman, and Arthur G. Kramer.

More specifically, this invention relates to the control of the transfer or carry mechanism associated with the several denominational orders or units of the totalizers and includes a novel control of said transfer mechanisms whereby the plurality of totalizers on each of the several lines of totalizers may be split or divided so as to create, from a certain number of totalizers of high capacity on each line, a greater number of totalizers of lower capacity on each of said lines.

For an illustrative example, a machine having a keyboard of fifteen denominational orders or units and three lines of totalizers which have been designated upper, front and back lines, is shown herein. The front and back lines each has nine totalizers thereon, and the upper totalizer line has ten totalizers thereon. Each of the 28 totalizers has a capacity of fifteen denominational units.

With applicant's invention each of the nine totalizers on the front and back lines, in one instance, can be separated or split into forty-five totalizers, each having a capacity of three denominational units, and the ten totalizers on the upper line can be separated or split into fifty totalizers each having a capacity of three denominational units; and in another instance such totalizers on said front and back lines can be separated or split into eighteen totalizers, nine of the eighteen totalizers each having a capacity of six denominational units and the other 9 of the 18 totalizers each having a capacity of nine denominational units, and said totalizers on the upper line can be separated into twenty totalizers,

ten of said twenty totalizers each having a capacity of six denominational units and the other ten of said twenty totalizers each having a capacity of nine denominational units; and in still another instance such totalizers on said front and back lines can be separated or split into twenty-seven totalizers, nine of the twenty-seven totalizers each having a capacity of three denominational units, nine more of the twenty-seven totalizers each having a capacity of nine denominational units, and the remaining nine of said twenty-seven totalizers each having a capacity of three denominational units, these last nine totalizers being used to automatically count 1 upon each adding operation of the machine, and said totalizers on the upper line can be separated or split into thirty totalizers, ten of said thirty totalizers each having a capacity of three denominational units, ten more of the thirty totalizers each having a capacity of nine denominational units and the remaining ten of said thirty totalizers each having a capacity of three denominational units, the last ten totalizers being used to automatically count 1 upon each adding operation of the machine; and in still another instance, and by the use of this same invention the nine totalizers on the front line and on the back line can be controlled to function as nine totalizers, each having the full capacity of fifteen denominational units, and the ten totalizers on the upper line at the same time controlled to function as ten totalizers each having the full capacity of fifteen denominational units.

From the above general description it is clear that by the use of applicant's novel variable split control mechanism, a machine having three lines of totalizers with nine totalizers on the front line, nine totalizers on the back line, and ten totalizers on the upper line, can be divided or split, so that the machine has a total capacity of 140 totalizers in one instance, 56 totalizers in another instance, 84 totalizers in another instance, and at the same time and by the use of the same mechanism the totalizers can be all rendered normal so that the machine has a capacity of 28 totalizers, each having the full denominational capacity of 15 units.

By the use of applicant's novel, variable split control mechanism the machine may be put in condition to be used for analysis work of various types. For example, many public utility companies wish to analyze the various amounts of consumption used by people who receive gas and electric service from those companies.

Briefly, this can be accomplished by setting the variable split control mechanism so as to

give a five-way split, namely, 3-3-3-3-3, which divides the machine into 140 totalizers, 139 of which are used to count the various amounts of consumption that are used by the various customers. They divide their consumption figures in those ending in 0, 2, 4, 6 and 8, and each of the three-way splits then is used to represent those digits 0, 2, 4, 6 and 8, and the control keys on the machine in the transaction banks are used to designate the tens and hundreds numbers preceding the units digits and 0, 2, 4, 6 and 8. For example, a customer who has used 247 units of consumption, the operator in making the analysis would press the 1 key in the highest split, and along with it would press the 24 transaction key. This key would select totalizer #24 of this split, and 1 would be added into that totalizer by the depression of the 1 key. Whenever a figure ends in an odd number, they use the next higher even number. Now for all customers who have used 247 units, the operator will press the same keys. The result of this analysis can be printed, which will tell the company how many customers use 248 or 247 units of consumption. Such figures may be obtained from the individual detail strips of the machine of the type shown in the Spurlino and Rauch Patent No. 2,361,662.

After the operator has analyzed all of the various consumptions, then a chart is used from which the operator obtains the charge for the groups of units and writes the amount the charges opposite the various consumption accumulations. The variable split control mechanism may be moved into another position to split the totalizers into groups having six and nine denominational orders and then the amounts from the different types of consumptions may be further analyzed in these two splits in the machine.

Such types of analysis may be used for breakdowns in consumptions in the different types of services, such as industrial services, commercial, domestic, rural, and other miscellaneous types of services which are sold by the various utility companies.

After all of these amounts are accumulated or added into the various totalizers under the different variable split control the totals may be printed from said totalizers by printing mechanism (not shown in this application), but which is substantially identical with that shown in the above mentioned Arnold Patent No. 2,141,332.

Central offices of chain stores may wish to analyze their various types of business from their different stores throughout the country and here again the variable split control mechanisms may be used to divide the various groups of totalizers into larger groups of totalizers of smaller capacities when higher capacity totalizers are not needed for the various analysis breakdowns. Again, in other types of businesses where inventory controls are to be analyzed, this mechanism renders the machine adaptable for uses in that type of work whereby the various items of the inventory may be divided, for example, into 140 different classes when the variable split control mechanism is used to split the totalizers from the normal 28 totalizers into the 140 totalizers, as above stated.

It is, therefore, an object of this invention to provide a novel variable split control mechanism for controlling the transfer or carry mechanism between various denominational orders of the totalizers so as to control the machine to split

the totalizers into variable numbers of totalizers of various denominational capacities, depending upon the positions into which the variable split control mechanism is set prior to the beginning of the first operation of the machine.

Another object of this invention is to provide a novel mechanism to control the transfer mechanisms between a certain plurality of denominational elements of the totalizers of a plurality of lines of totalizers with a single manipulative member to variably control the different types of splits in the totalizers, as desired, depending upon the particular type of work which it is desired to have the machine do.

Another object of this invention is to provide a novel mechanism to control the transfer mechanisms between certain denominational elements of the totalizers to cause a split in the totalizers on all three lines by a common mechanism, and at the same time cause the totalizers split off from the main group of totalizers to automatically count 1 for each operation of the machine into each of the selected totalizers on each of the three different lines.

Another object of this invention is to provide a novel form of variable split control mechanism adaptable for use in machines having a plurality of totalizer lines, each line having thereon a plurality of interspersed totalizers.

A still further object of the present invention is to provide novel mechanism for controlling the transfer mechanism intermediate certain of the denominational elements of a plurality of totalizers on a plurality of lines, and in addition to provide a differentially adjustable means to control the effectiveness of the means to determine which of the plurality of means that controls the transfer mechanisms shall become effective for any particular operation.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In said drawings:

Fig. 1 is a diagrammatic view of the keyboard of the machine embodying the present invention.

Fig. 2 is a sectional view alongside of one of the amount banks, showing the three totalizer lines, the differential mechanism therefor, and a portion of the transfer mechanism associated with each of the three lines of totalizers.

Fig. 3 is a side elevation of a portion of the mechanism for controlling the transfer means intermediate certain of the groups of totalizers and also shows a differentially movable member for controlling said means.

Fig. 4 is a view in side elevation showing the mechanism for effecting the automatic count in a portion of the totalizers split off from the main body of totalizers.

Fig. 5 is a detail view of a portion of the mechanism for controlling the mechanism shown in Fig. 4.

Fig. 6 is a plan view, partly broken away, showing the variable split control mechanism and the automatic item count mechanism.

Fig. 7 is a detail of the split control member intermediate the ninth and tenth denominational orders.

Fig. 8 is a detail of the split control member intermediate the sixth and seventh denominational orders.

Fig. 9 is a detail of the split control member intermediate the third and fourth denominational orders.

GENERAL DESCRIPTION

Described in general terms, the machine embodying the present invention is of the same general type as that disclosed in the above mentioned Shipley patents, which disclose a machine having three lines of a plurality of interspersed totalizers. In the present instance the front and back lines are each provided with nine totalizers, and the upper line has ten totalizers. All of these totalizers, as shown by the diagrammatic view of the keyboard, have a capacity of 15 denominational units, and there is one set of differential mechanisms, such as that shown in Fig. 2, for each bank of keys shown in Fig. 1. These totalizers are operated by the differential mechanisms under the control of these amount keys while the selection of the totalizers to be operated is accomplished through differential mechanism shown in the Shipley patents under the control of the three banks of keys marked "Transaction Rows," shown in Fig. 1.

The above amount differential mechanisms serve to adjust printing mechanisms such as those shown in the above mentioned Arnold Patent 2,141,332, whereby the results obtained in the various totalizers may be printed.

The present invention, however, as above mentioned, concerns particularly novel mechanism for controlling the transfer mechanisms between certain denominational orders of the totalizers, whereby the totalizers may be separated or split into variable numbers of totalizers of lesser denominations than the normal totalizers of 15 denominational units.

DETAILED DESCRIPTION

Framework, operating mechanism and releasing mechanism

Only so much of the framework of the machine, the machine operating mechanism and the machine releasing mechanism, has been shown as is necessary, and for a further description thereof reference may be had to the above mentioned patents.

The mechanism in general is supported between side frames 21 (Figs. 2 and 6). A main operating shaft 22, used to operate the mechanism of the machine may be driven by hand or by motor as mentioned in the above mentioned Shipley patents. A release shaft 23 or key lock line, as it is known in this art, is shown in Fig. 3, which shaft is given a clockwise rotation upon depression of the motor bar or any of the keys in the total row, as shown diagrammatically in Fig. 1.

Keyboard

The keyboard of the machine is diagrammatically shown in Fig. 1 and consists of a motor bar 24, a row of total keys 25 marked "Read and Reset," a row of transaction keys 26 marked 1 to 9; a row of transaction keys 27 marked 10 to 18; a row of transaction keys 28 marked 19 to 27; and fifteen rows of amount keys 30. There is also projecting through a cabinet 31 a lever 32, to be hereinafter described, which lever controls the novel mechanism for controlling the transfer elements intermediate various certain denominational elements or wheels of the several totalizers on each of the three lines.

The machine proper, including all of the printing mechanism thereof, is enclosed in this suit-

able cabinet 31 (Figs. 2 and 3) having the necessary hinged sections for the operator to gain access to certain parts of the machine whenever necessary. All of the hinged sections, wherever necessary, are provided with suitable locks to prevent unauthorized persons from having access to the inner parts of the machine.

A retaining lever 33, associated with the lever 32, also projects through an opening in the cabinet 31. The purpose of this lever will be hereinafter described.

Amount keys

As above mentioned, there are fifteen banks of amount keys 30 (Figs. 1 and 2) which amount banks are substantially identical with the amount banks shown and described in the above mentioned Shipley patents, and therefore, but a brief description thereof will be given herein. The keys 30 are slidably mounted in key frames 35, supported at their upper and lower ends by rods 36 and 37, respectively, carried by the machine side frames 21. Each of these keys 30 cooperates with a control bar and a locking bar (not shown), and is held in its normal outer position by the usual key restoring spring 38. The keys are released near the end of the operation of the machine in the manner shown and described in the United States Letters Patent to B. M. Shipley No. 1,789,418, dated January 20, 1931.

Cooperating with each bank of keys is a zero stop pawl 39, the function of which is to stop the differential mechanism in the zero position when no key in that respective bank is depressed. The zero stop pawls 39 and their functions are fully illustrated and described in the above mentioned Shipley patents, and it is therefore thought unnecessary to go into any further description thereof.

Control keys

The three rows of control keys 26, 27 and 28, are mounted in key frames (not shown) but similar to the frames 35, and are for the purpose of selecting totalizers on the upper, back and front lines, under the control of keys 26, 27 and 28, respectively.

These keys and their means, which they control for the selection of the totalizers, are substantially the same as those described in the above mentioned Shipley patents, and therefore no further description thereof is thought necessary herein.

Total row

The row of total keys 25 are for the purpose of controlling the machine for read and reset operations, or sub-total and total, respectively, and control mechanism substantially the same as that described in the above mentioned Goldberg Patent No. 2,175,346, to effect such total and sub-total operations.

Motor bar

The motor bar 24 is used to release the machine for operation in adding operations, after the depression of the proper amount keys to record the desired transactions, and in connection with whichever one of the transaction keys 26, 27 or 28 is to be depressed for that transaction.

Differential mechanism

The differential mechanisms of the machine are employed to differentially operate the different totalizers, and to select them for operation, and also to set type carriers in the printing mecha-

nism as controlled by the banks of keys in adding operations and by the totalizers in total and sub total operations.

Amount differential mechanism

The amount differential mechanism will be briefly described first. There is one complete differential unit for each amount bank, but as they are all identical in construction and operation, only one will be described.

Each amount differential unit (Fig. 2) is supported by the usual hangers 41, mounted on rods 42 and guided at their upper ends between the key frames 35.

To drive the differential mechanism of the machine, the drive shaft 22 is provided with a plurality of pairs of cams 43, each pair cooperating with rollers 44 (only one of which is shown) carried by a Y-shaped lever 45, of which there is one for each bank of keys in the machine. This lever 45 is pivoted to the hanger 41.

Loosely mounted on the studs 46, carried by the hangers 41, are differentially movable actuators 47 carrying racks 48 and transfer arms 49 for operating totalizer pinions 50. There are three sets of racks 48 and three sets of transfer arms 49 to cooperate, one set each with the totalizer pinions 50 on the upper, front and back totalizer lines. The levers 45 are connected by links 61 to driving segments 62, loose on the studs 46. The driving segments 62 adjacent the banks of amount keys are connected to the differentially movable actuators 47 by latches 63, each supported by an arm 64 and a lever 65 pivoted on the corresponding actuator 47. Springs 66 pull the latches into engagement with shoulders on the driving segments 62.

When the segments 62 are driven by their cams 43, the differentially movable actuators 47 are carried with their latches up to points where the forwardly extending arms of the levers 65 engage the inner ends of the depressed amount keys 30. Such engagement results in the disengagement of the latches from the driving segments 62 and the engagement of the forward ends of the latches with the particular one of a series of notches 67 in a bar 68 supported by the particular hanger 41, which is opposite the latch when it is disengaged. Upon the return movement of each driving segment 62 to normal position, a pin 69 (Fig. 6) mounted on the associated differentially movable actuator 47 is engaged by the inside of the driving segment 62, and said actuator 47 is returned thereby to its normal position.

If a key is not depressed in the bank, the zero stop pawl 39 therefor operates the latch to arrest the differentially movable actuator 47 in its zero position. However, when a key is depressed the zero stop pawl 39 is moved out of its operative position by means fully described and illustrated in the above mentioned Shipley Patent No. 1,619,796.

Totalizers

As has been previously mentioned, there are three lines of totalizers, namely, an upper line, a back line, and a front line. The upper line has ten interspersed totalizers each consisting of 15 totalizer pinions or wheels 50. The front line and the back line each has nine totalizers, each of which consists of 15 denominational pinions or totalizer wheels 50. This type of totalizer is fully illustrated and described in the above mentioned Shipley Patent No. 1,619,796, and the totalizer lines are arranged to be moved into and

out of engagement with their respective sets of racks 48, carried by the differential actuators 47. The appropriate totalizer on each of the lines, as above mentioned, is selected for operation under control of the keys 26, 27 and 28, shown diagrammatically in Figure 1, and under control of totalizer engaging selecting mechanism as shown in the Shipley Patents Nos. 1,619,796 and 1,749,960.

10

Transfer mechanism

When one of the totalizer wheels 50 passes from "9" to "0," a transfer mechanism is operated for causing "1" to be added upon the totalizer wheel 50 of next higher order. Pivotally secured to the differentially movable actuators 47 are three transfer arms 49, each having two teeth like the teeth of the racks 48. These arms are in the same plane with said racks 48.

The transfer tripping mechanism associated with the three arms 49 for the three totalizer lines is identically the same. Therefore, the tripping mechanism for one denominational order of a totalizer on the front line only will be described, the same reference numbers being given to the transfer elements for all three lines. Pivoted to the arm 49 (Fig. 2) are levers 76, one on each side of said arm. These levers carry a pin 77 held in contact with a projection 78 integral with the rack 48 by a spring 79 stretched between the lever and the differential actuator 47. This spring, during the clockwise movement of the differential rack 48, holds the arm 49 in such a position that the pin 77 is locked in a recess in the projection 78 so that the rack 48 and arm 49 move as a unit. The lever 76 has secured thereto a square stud 80, which normally abuts an end 81 of a transfer lever 82 mounted on a stud 83 on the hanger 41 when the differential rack 48 arrives at zero position. The differential actuator 47 and the rack 48 are normally given one unit of movement counterclockwise beyond zero to their normal position, and consequently the abutment of the stud 80 with the end 81 causes the transfer arm 49 to be held, whereby the pin 77 becomes disengaged from the notch in the extension 78, as is clearly shown on Figure 2. Consequently the differential actuator 47 and racks 48 normally move one step farther than the transfer arm 49.

Fast on a short shaft 85 supported by the hanger 41 is a transfer trip lever 86 (Figs. 2, 3, 4 and 6) having a projection 87 which lies in the path of a long tooth 88 on the totalizer wheel 50 of next lower denomination. Also fast on the shaft 85 is an arm 89 carrying a flattened pin 90, held by a torsion spring 92, in engagement with a shoulder 91 in an opening in the transfer lever 82, one end of said spring 92 being secured to the hanger 41 and the other end to the transfer trip lever 86.

As a totalizer wheel 50 passes from "9" to "0" the long tooth 88 thereof engages the projection 87 and rocks the lever 86 counterclockwise (Fig. 2). This movement disengages the pin 90 from the shoulder 91 and a spring 93 rocks the lever 82 clockwise and moves the end 81 away from the square stud 80 and brings a shoulder 94 into the path of movement of the stud 80 to regulate the movement of the transfer arm 49. When this occurs, the arm 49 remains locked to the rack 48 during the extra unit of movement past the zero position, which said transfer arm 49 receives, thereby causing "1" to be added upon the totalizer wheel 50 of next higher denominational order.

All displaced transfer devices are restored to

their normal positions at the next operation of the machine by a three-armed lever 95, loose on the stud 46. The lever 95 carries a pin 96 engaged by an edge 97 of the drive segment 62, in the next lower bank, near the end of the clockwise movement of said segment. When the pin 96 is thus engaged by the segment 62, the three-armed lever 95 strikes edges 98 of the levers 82 and rocks said levers counterclockwise until the pins 90 again engage the shoulders 91, and the transfer trip levers 86 are restored to their normal positions by the springs 92.

Totalizing operations

During totalizing operations, which consist of either read or reset operations, the machine is under control of the keys 25 (Fig. 1). Under control of these keys a plate 100 (Figs. 4 and 6) is differentially positioned, depending upon the key which is depressed. During such total and subtotal operations the main drive shaft 22 is given two complete rotations in a clockwise direction. During the first cycle of movement or first rotation of the shaft 22, all of the previously tripped transfer devices are restored to their normal positions, and the differentials all stop in the zero positions. During the second cycle a shaft 101 (Fig. 2) and a segment 102 thereon, are moved counterclockwise to rock a segmental lever 103 slightly clockwise to straighten out a toggle, consisting of links 104 and 105, the latter of which is pivoted to a lever 106 carrying a flattened stud 107 adapted to cooperate with teeth 108 in a reset spider 109 having an arm 110 surrounding a stud 111 carried by the latch lever 65. When the links 104 and 105 are straightened, a pawl 112 is moved into the path of the long tooth 88 of the totalizer wheel 50. Therefore, during the second cycle of a totaling operation, when the totalizer wheel is rotated counterclockwise and when the long tooth strikes the pawl 112, it rocks said pawl counterclockwise (Fig. 2) and through the links 104 and 105 rocks the lever 106 in a clockwise direction, whereupon the flattened stud 107 engages the tooth 108 opposite it at that particular time, whereupon the reset spider 109 is stopped, which through its engagement with the stud 111 disengages the latch 63 from the driving segment 62 to set the differential mechanism in a position according to the amount which was taken from the associated totalizer wheel.

This mechanism is fully illustrated and described in the Shipley Patent 1,619,796 above mentioned.

Variable split control and item count.

As has been pointed out earlier in this specification, a novel mechanism has been provided for splitting the totalizers on the three totalizer lines, namely, the upper, back and front lines, into a variable number of smaller denominational capacities under the control of the manually operable, differentially adjustable or positionable lever 32 (Figs. 1 and 3).

When this lever 32 is set in position 1 or neutral position, all twenty-eight of the totalizers, that is nine on each of the front and back lines and ten on the upper line, function in their normal manner with each totalizer having its full capacity of 15 denominational orders.

When the lever 32 is moved into position 2, it controls mechanism to split the totalizers on all three lines into a greater number of totalizers, namely, forty-five totalizers on each of the front and back lines and fifty totalizers on the upper

line, each of said total of 140 totalizers having a denominational capacity of three orders or units.

When the lever 32 is moved into position 3, it operates this same mechanism to split the totalizers on the front and back lines so that each of said lines will have eighteen totalizers, nine of which have a denominational capacity of 6 units and the other nine totalizers each having a capacity of 9 denominational units, and the totalizers on the upper line are split so that there will be twenty totalizers on this line, ten of which will have a capacity of 6 denominational units and ten of which will have a capacity of 9 denominational units.

When the lever 32 is moved into position 4, it controls this same mechanism to split the totalizers on the front and back lines so that there will be twenty-seven totalizers on each of the two lines, nine of which will have a denominational capacity of 3 units, nine of which will have a capacity of 9 denominational units, and the last nine of which will have a capacity of 3 denominational units. These last nine totalizers will be used for item counting and for this purpose the lever 32 controls, in addition to the same mechanism above mentioned, a special mechanism for causing these nine totalizers to be converted into item counting counters. The lever 32, when moved into position 4, causes the upper line to be split into thirty totalizers, ten of which have a denominational capacity of 3 units, ten of which have a denominational capacity of 9 units, and ten of which are used for item counting and have a capacity of 3 denominational units each.

As pointed out earlier, to cause the totalizers to be split into the variable number of totalizers above mentioned, the transfer mechanisms between certain denominational orders of the totalizers on all of the lines are controlled to accomplish this result.

To cause the split to occur in the various places above mentioned, the transfer mechanisms between the denominational elements of the totalizers, at the points indicated by the splits, as shown in Fig. 1, are prevented from tripping, and consequently there can be no carry from, for example, the third denominational unit into the fourth denominational unit, thus making the fourth denominational unit the normal units order of a split-off totalizer, as indicated by position 2.

As indicated by this position, the splits occur between the third and fourth, the sixth and seventh, the ninth and tenth, and between the twelfth and thirteenth denominational orders of the totalizers, and consequently the transfer mechanisms between these orders are prevented from operating when the lever 32 is moved into position 2.

When the lever is moved into position 3 the transfer mechanisms between the 6th and 7th denominational orders are prevented from actuating, to accomplish the split as indicated by position 3.

When this lever 32 is in position 4 the transfer mechanisms between the third and fourth denominational units are prevented from operating to accomplish the split at this position. However, the transfer mechanisms between the 12th and 13th denominational orders in this particular case, in order to create an item-count counter, instead of being prevented from being operated are caused to operate each and every time the machine is operated, so that the 13th order, as indicated by the diagrammatic keyboard in Fig.

1, then becomes the units order of the item count counter, and consequently one will be added into this units denominational order each and every time the machine is operated.

Variable split control

The mechanism for controlling the variable splits above mentioned will now be described, with particular reference to Figs. 3 and 6 to 9.

Pivoted to the lever 32 is a link 121, which is also pivoted to a gear segment 122 loose on the rear shaft 101. This gear segment 122 meshes with a pinion 123, secured to a shaft 124 carried by the side frames 21. Also secured to the shaft 124 are four disks 125, 126, 127 and 128, having four positions indicated thereon, which four positions correspond to the four positions of the lever 32, as indicated in the diagrammatic view (Fig. 1).

Cooperating with each of the cams 125 to 128 is a roller 131, carried by a lever 132, pivoted on the rear shaft 101. A spring 133 connected to each of the levers 132, holds its respective roller 131 in contact with its associated disk 125 to 128. Each of the springs 133 is connected to a lever 134, pivoted on a stud 135, carried by the hanger 41 associated with that particular denominational order of the totalizer. A stud 136 helps to guide the lever 134 during its movements. Each of the levers 134 has a notch 137 which engages the previously described pin 96 on the transfer restoring lever 95 associated with a particular denominational order of the totalizer. Each lever 134 carries a stud 138 held normally, by the spring 133, in front of the lever 132, below a shoulder 139 thereon.

There is a lever 132 and a lever 134 associated with the transfer restoring lever 95 between the third and fourth denominational elements, between the sixth and seventh denominational elements, between the ninth and tenth denominational elements, and between the twelfth and thirteenth denominational elements of the totalizers.

The disks 125, 126, 127 and 128 are notched in the following manner:

Disk 125 has a notch 140 in the 2 and 4 positions, disk 126 has notches 140 in the 2 and 3 positions, disk 127 has a notch 140 in the 2 position, and disk 128 has a notch 140 in the 2 position.

Whenever the lever 32 is moved from the neutral position shown in Fig. 3, into any of its other three positions, the link 121 and gear segment 122, through the pinion 123, turn the shaft 124, and consequently the four disks 125, 126, 127 and 128, and set them in positions corresponding to the position in which the lever 32 is set.

As shown in Fig. 3, the lever 32 is in position 1 or the position marked also "Neutral," wherein each of the disks 125 to 128 has no notches 140, and consequently the rollers 131 on the levers 132 cooperate with the true peripheries of these disks and hold the levers 132 in the positions shown when the transfer restoring levers 95 are rocked clockwise in the manner previously described, which clockwise movement of these members rocks the levers 134 counterclockwise against the tension of the springs 133, and raises the studs 138 from the position shown in Fig. 3 to a position above and in front of the shoulders 139 of the levers 132, but since the rollers 131 all cooperate with the true peripheries of the disks 125 to 128, the spring 133 cannot rock any of the levers 132 in a counterclockwise direction, and

therefore, at the end of the operation, the springs 133 restore all four of the transfer restoring levers 95 to their normal positions, as shown in Fig. 3.

However, assume that the lever 32 is moved into position 2, which rotates the shaft 124 counterclockwise to bring position 2 of all of the disks 125 to 128 opposite the rollers 131 of the levers 132.

With the parts in these positions, when the four transfer restoring levers 95 are rocked clockwise, they rock the four associated levers 134 counterclockwise, whereupon the studs 138 are moved upwardly in front of the notches 139, and due to the fact that each of the disks 125 to 128 inclusive has a notch 140 in its position 2, the springs 133 rock all four of the levers 132 counterclockwise and position the shoulders 139 of said levers beneath the studs 138 of the levers 134, and consequently the transfer restoring levers 95 are locked in their restoring positions which holds the transfer levers 82 in the positions shown in Figs. 3 and 4, so that, even though any of the transfer trip levers 86 are tripped by the long teeth 88 of the denominational elements of next lower order, the transfer levers 82 cannot be rocked in a clockwise direction by their springs 93, due to the fact that they are being held in the positions shown in Figs. 3 and 4 by the transfer restoring levers 95, and consequently the torsion springs 92 will immediately restore the tripped levers 86 and their connected arms 89 to their normal positions, thus preventing any transfers from taking place between the third and fourth denominational orders, between the sixth and seventh denominational orders, between the ninth and tenth denominational orders, and between the twelfth and thirteenth denominational orders of the totalizers. As is clearly shown in Figs. 3 and 4, the opening in each of the levers 82 is large enough to provide for the movement of each pin 90 on its arm 89 when the levers 82 are held in the positions shown in Figs. 3 and 4, by the restoring lever 95.

Therefore, the totalizers on the three totalizer lines are split into a greater number of totalizers of smaller denominational orders, as has been above pointed out.

When the lever 32 is moved into position 3, the transfer levers 82 between the 6th and 7th denominational orders of the totalizers are held in their untripped positions due to the fact that the disk 126 is the only disk which has a notch 140 in the position 3, and consequently the lever 132 associated with this particular denominational order is the only lever which can lock the lever 134 in its moved position by the shoulder 139. The disks 125, 127 and 128 having no notches 140 in position 3, hold the levers 132 associated with these three disks in their normal positions as shown in Fig. 1, and consequently the split at this time in the totalizer lines will be between the 6th and 7th denominational orders only.

When the lever 32 is moved into position 4 a split will occur between the 3rd and 4th denominational orders because in this position only the disk 125 has a notch 140 in position 4, and consequently the lever 132 associated with this denominational order is the only one which can be rocked counterclockwise by its spring 133 to lock the lever 134 and the associated transfer restoring lever 95 in their moved or effective positions.

During the movement of the lever 32 from one position to another the disks 125, 126, 127 and

128, as the case may be, rock the levers 132 clockwise by engagement with the rollers 131 thereof when the disks are moved into such positions that there are no notches 140 opposite the rollers 131. In other words, when the lever 32 is moved from position 2 to position 3, the disks cam the levers 132 back to the position shown in Fig. 3, except the lever associated with the disk 126, which has a notch 140 in position 3 and consequently this lever will remain in a position to lock the lever 134 associated with the particular denominational order.

Item count

When the lever 32 is moved into position 4, in addition to its controlling the totalizers for a split between the third and fourth denominational orders, it also sets up a condition whereby mechanism is controlled to cause the transfer trip levers 86 and their connected arms 89 to be automatically rocked during each operation of the machine. This mechanism shown in Figs. 4, 5 and 6 will now be described.

The transfer trip lever 86 intermediate the 12th and 13th denominational orders for the back totalizer line has a finger 141 engaging a stud 142 carried by an arm 143 pivoted on the rear shaft 101. This stud 142 projects through a lever 144, which is pivoted on the rear shaft 101 and carries a roller 145 cooperating with the periphery of a disk 146 secured to the shaft 124, which it will be remembered is moved differentially by the lever 32. This disk 146 has a notch 153 in position 4 corresponding to position 4 of the lever 32 and corresponding to positions 4 on the other disks 125 to 128 inclusive.

When the lever 32 is moved into position 4 it rocks the shaft 124 counterclockwise and positions the disk 146 to bring the notch 153 beneath the roller 145. When this occurs a spring 147 (Fig. 4) rocks an arm 148 clockwise. This arm 148 is pivoted on the shaft 124 and is connected by a bail 149 to an arm 150, which in turn is connected by a link 151 to the lever 144, and, therefore, the rocking of the arm 148 by the spring 147, when the notch 153 of the disk 146 is positioned beneath the roller 145, rocks the lever 144 clockwise, whereupon the stud 142 by its contact with the finger 141 rocks the transfer trip lever 86 counterclockwise, which rocks the trip arm 89 counterclockwise and disengages the stud 90 from the shoulder 91 in the transfer lever 82, thus permitting the spring 93 to rock the transfer lever 82 clockwise to position the shoulder 94 opposite the square stud 80 in the transfer arm 49, so that when the differential is restored to its normal position as previously described, "1" will be added into the item count counter, which consists of the three highest denominational totalizer wheels 50 on the back line.

As long as the lever 32 is in the position 4, the notch 153 of the disk 146 will remain below the roller 145, because the transfer trip lever 86 and its trip arm 89 will be held in tripped position, and consequently the transfer lever 82 will be held in its clockwise position with the shoulder 94 remaining opposite the square stud 80, so that "1" will be automatically added into this denominational order each and every operation of the machine.

When the lever 32 is in position 1, 2 or 3, the roller 145 is held against the true periphery of the disk 146 and consequently the spring 147 cannot function, and, therefore, the transfer trip

lever 86 and its trip arm 89 will not be operated by the lever 144.

In order that the item count counters on the upper and front lines may be operated simultaneously with the item count counters on the back line, there is provided a three-armed lever 156, which is supported by the differential tie rod. Each arm of this three-armed lever 156 has a stud 157 engaged by a forked arm 158. The arm 158 associated with the back totalizer line is connected by a bail 159 to the previously described arm 143, which carries the stud 142 to operate the transfer trip lever 86 for the back line. The arms 158 associated with the front and upper lines are each connected by a bail 160 to an arm 161, which are pivoted on the upper and front shafts 101 associated with the upper and front totalizer lines. Each arm 161 carries a stud 162, which cooperates with a finger 163 on the transfer trip levers 86 associated with the front and upper totalizer lines.

Therefore, it can be seen that, whenever the transfer trip lever 86, associated with the rear totalizer line is tripped by the stud 142, through the lever 156 and the mechanism just described, the studs 162 will trip the transfer levers 86 associated with the upper and front totalizer lines. Consequently "1" will be added into the item counters on the upper and front totalizer lines whenever the item count totalizer on the back line is operated to count "1."

Disabling of item count

Whenever totals or sub-totals are to be taken from the totalizers, it is desirable that the item count mechanism should not function. Therefore, mechanism is provided to prevent the operation of the item count mechanism under such conditions.

This mechanism includes a lever 165 (Figs. 4 and 6) pivoted on the rear shaft 101 associated with the back totalizer line, which lever carries a pin 166 projecting into a slot in the previously described arm 148. This lever 165 also carries a roller 167, which cooperates with the total control plate 100. This total control plate 100 is moved clockwise during machine operations whenever any of the total control keys 25 for either a re-add or reset operation is operated, and consequently a surface 168 of this plate 100 is moved opposite the roller 167 of the lever 165, with the result that this lever 165 cannot be rocked in a counterclockwise direction by the spring 147 and therefore, since this lever 165 cannot be rocked, the arm 148 cannot be rocked, and consequently the pin 166 will not be moved upward, and therefore, no item count can take place during any total or sub-total operation.

When the total plate 100 is in the add position, a low portion 169 of the plate is opposite the roller 167, and consequently the lever 165 can be rocked counterclockwise at that time by the spring 147 and arm 148 when an item count is to be effected with the lever 32 in position 4.

Interlock between machine release means and control lever 32

As earlier pointed out in this specification, the machine release shaft 23 or key lock line is rocked in a clockwise direction upon the release of the machine in a manner previously described in the above mentioned Shipley Patent No. 1,619,796. This shaft 23 has secured thereto an arm 171. Pivoted on the upper shaft 101

associated with the upper totalizer line is the previously mentioned lever 33, which has a finger 172 and a roller 173, which roller cooperates with four notches 174 in the lever 32, and is held in engagement with one of the notches 174 by a spring 175, stretched between a stud on the lever 33 and a stud on the lever 32.

To prevent the machine from being released while the lever 32 is being moved from one position to another, the lever 33 is manually rocked in a clockwise direction, which moves the finger 172 above the arm 171, and at the same time disengages the roller 173 from one of the notches 174, depending upon the position in which the lever 32 was standing. Now, with this disengagement of the roller 173, the lever 32 may be moved into any one of its positions, 1, 2, 3 or 4, without any danger of the machine being released because the release shaft 23 is positively prevented from any clockwise movement by the finger 172 of the lever 33. After the lever 32 has been set in the desired position the operator releases the lever 33 and the spring 175 rocks said lever 33 counterclockwise and engages the roller 173 with the appropriate one of the notches 174, depending upon the position into which the lever 32 has been moved.

Since the operations of all the parts have been clearly described, it is not thought necessary to give any further description of the operation of the mechanism.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described, the combination of a plurality of lines of totalizers; actuators for said totalizers; a plurality of amount-determining devices to control said actuators; transfer means intermediate the denominational orders of the totalizers; a plurality of means associated with one of the lines of totalizers to render the transfer means between a plurality of denominational orders of the totalizers on said line ineffective, said plurality of means being normally ineffective; devices controlled by said plurality of means to render ineffective the transfer means of corresponding denominational orders of the totalizers on the remaining lines of totalizers and differentially adjustable means to control said plurality of means to determine which of said plurality of means shall become effective.

2. In a machine of the class described, the combination of a plurality of lines of totalizers; actuators for said totalizers; a plurality of amount-determining devices to control said actuators; transfer means intermediate the denominational orders of the totalizers; a plurality of means associated with one of the lines of totalizers to render the transfer means between a certain plurality of denominational orders of the totalizers on said line ineffective, said plurality of means being normally ineffective; devices common to the remaining lines of totalizers and controlled by said plurality of means to render ineffective the transfer means corresponding to said plurality of denominational orders of the totalizers on said remaining lines of totalizers; differentially adjustable means cooperating with said

plurality of means to control the effectiveness thereof; and a device adapted to be moved into any of a plurality of positions to actuate the differentially adjustable means to determine which of said transfer means is to be rendered ineffective by said plurality of means, depending upon the position into which said device is moved.

3. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizers to restore all tripped transfer means to normal positions; devices operated by a certain plurality of said restoring means in the corresponding denominational orders of all lines of totalizers and adapted to be set in positions to lock certain plurality of restoring means in operated positions when said devices are in said set positions to prevent tripping of the associated transfer means; and differentially adjustable means to determine which of said devices shall become effective to lock their associated restoring means.

4. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizers to restore all tripped transfer means to normal position; devices operated by a certain plurality of said restoring means in the corresponding denominational orders of all of said lines of totalizers and adapted to be set in positions to lock the associated transfer means in untripped positions; differentially adjustable means; means intermediate said devices and said differentially adjustable means; and a member adapted to be moved into a plurality of different positions to cause said intermediate means to retain certain of said devices in said set positions when said member is moved into one of its positions of adjustment, and to cause said intermediate means to retain certain other of said devices in said set positions when said member is moved into another of its positions of adjustment.

5. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizers to restore all tripped transfer means to normal positions; devices controlled by a certain plurality of said restoring means in the corresponding denominational orders of all of said lines of totalizers and adapted to be set in positions effective to lock the associated transfer means in untripped positions; differentially adjustable means cooperat-

ing with said devices to control the effectivity thereof; and a member adapted to be moved into a plurality of different positions to cause said adjustable means to retain in effective positions certain of said devices when said member is moved into one of its positions of adjustment, and to cause said adjustable means to retain in effective positions certain other of said devices when said member is moved into another of its positions of adjustment, and to cause said adjustable means to retain in effective positions the remainder of said devices when said member is moved into a certain other one of its positions of adjustment.

6. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizers to restore all tripped transfer means to normal positions; devices controlled by a certain plurality of said restoring means in the corresponding denominational orders and adapted to be set in positions to lock the associated transfer means in untripped positions; adjustable means cooperating with said devices to render certain of said devices effective when said adjustable means is moved into one of its positions of adjustment, and to render certain other of said devices effective when said adjustable means is moved into another of its positions of adjustment, and to render the remainder of said devices effective when said adjustable means is moved into a certain other one of its positions of adjustment; and a manually operable means to actuate said adjustable means.

7. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizer to restore all tripped transfer means to normal positions; devices controlled by a certain plurality of said restoring means in the corresponding denominational orders and adapted to be set in positions to lock the associated transfer means in untripped positions; mechanism associated with the transfer means of a particular denominational order to automatically trip the transfer means for that order associated with all of said lines of totalizers, said mechanism being normally ineffective; adjustable means cooperating with said devices and with said mechanism; and a member adapted to be moved into a plurality of positions of adjustment to cause said adjustable means to render certain of said devices effective and for rendering said mechanism effective when said member is moved into one of its positions of adjustment, and to cause said adjustable means to render certain other of said devices effective when said member is moved into another of its positions of adjustment.

8. In a machine of the class described, the combination of a plurality of lines of totalizers;

actuators for said totalizers; a plurality of amount determining devices to control said actuators; transfer means intermediate the denominational orders of the totalizers, said transfer means adapted to be tripped by the next lower order wheels to cause a carry to the adjacent higher order wheels when said lower order wheels pass from 9 to 0; means common to the transfer means of all of said lines of totalizers to restore all tripped transfer devices to normal positions; devices controlled by a certain plurality of said restoring means in the corresponding denominational orders and adapted to be set in positions to lock the associated transfer means in untripped positions; mechanism adapted to automatically trip the transfer means of all of said lines associated with one of said certain plurality of restoring means; adjustable means cooperating with said devices and with said mechanism; and a member adapted to be moved into a plurality of different positions of adjustment to cause said adjustable means to render certain of said devices effective when said member is moved into one of its positions of adjustment, and to cause said adjustable means to render certain other of said devices effective, and to render said mechanism effective when said member is moved into another position of its adjustment, and to cause said adjustable means to render the remainder of said devices effective, and also to prevent said mechanism from becoming effective when said member is moved into a certain other one of its positions of adjustment.

9. In a machine of the class described, the combination of a plurality of lines of totalizers each line having a plurality of totalizers; actuators for said totalizers; a plurality of amount-determining devices to control said actuators; transfer means associated with each line of totalizers and common to all totalizers on each line intermediate the denominational orders of the totalizers, said transfer means adapted to be tripped by the next lower order wheels to cause a carry to the adjacent higher order wheels when said lower order wheels pass from 9 to 0; means associated with the transfer mechanism of a certain one of the denominational orders of the totalizers on one of said totalizer lines to automatically trip said transfer mechanism independently of the wheels of next lower order, said means being normally ineffective; means actuated by said associated means to automatically trip the transfer means corresponding to said certain denominational order on the remaining totalizer lines; differentially adjustable means cooperating with said associated means to control the effectivity thereof; and a member adapted to be moved into a plurality of positions of adjustment to control said differential means.

10. In a machine of the class described, the combination of a plurality of lines of totalizers each line having a plurality of totalizers; actuators for said totalizers; a plurality of amount-determining devices to control said actuators; transfer means associated with each line of totalizers and common to all totalizers on said line and intermediate the denominational orders of the totalizers; a device associated with the transfer means of a certain denominational order of the totalizers on one of said lines of totalizers, and adapted to trip said transfer means to cause the adjacent higher order wheels of said totalizers on said one line to add 1 each operation of the machine, said device being normally

held in an ineffective position; means including a single member actuated by said device to trip the corresponding denominational order of transfer means of the totalizers on the remaining lines of totalizers; a member adapted to be moved into a plurality of positions of adjustment; and means actuated by said member to control the effectivity of said device.

11. In a machine of the class described, the combination of a plurality of lines of totalizers; actuators for said totalizers; a plurality of amount-determining devices to control said actuators; transfer means intermediate the denominational orders of the totalizers; a device associated with the transfer means of a certain denominational order of the totalizer on one of said lines, and adapted to trip said transfer means to cause the adjacent higher order wheels of said totalizer on said one line to add 1 each operation of the machine, said device being normally held in an ineffective position; means associated with all the remaining lines of totalizers and operated by said device to trip the corresponding transfer means of said lines when said device is rendered effective; a member adapted to be moved into a plurality of positions of adjustment; and means actuated by said member to control the effectivity of said device.

12. In a machine of the class described, the combination of a plurality of lines of totalizers; actuators for said totalizers; a plurality of amount-determining devices to control said actuators; transfer means intermediate the denominational orders of the totalizers; a device associated with the transfer means of a certain denominational order of the totalizer on one of said lines of totalizers, and adapted to trip said transfer means to cause the adjacent higher order wheels of said totalizer on said one line to add 1 each operation of the machine, said device being normally held in an ineffective position; means common to all of the remaining lines of totalizers and operated by said device; means operated by said common means and cooperating with the corresponding transfer means of said remaining lines of totalizers to trip said corresponding transfer means when said device is rendered effective; a member adapted to be moved into a plurality of positions of adjustment; and means actuated by said member to render said device effective when said member is moved into a certain one of its positions of adjustment.

13. In a machine of the class described, the combination of a plurality of lines of totalizers; actuators for said totalizers; a plurality of amount-determining devices to control said actuators; transfer means associated with each totalizer line; mechanism having an add position and total-taking positions to control the machine to take totals from all of said totalizers; a device associated with the transfer means of a certain denominational order of the totalizer on one of said lines of totalizers, and adapted to trip said transfer means to cause the adjacent higher order wheels of said totalizer on said one line to add 1 each operation of the machine, said device being normally held in an ineffective position; means controlled by said device to trip the corresponding order of transfer means for the remaining totalizer lines a member adapted to be moved into a plurality of positions of adjustment; means actuated by said member to render said device effective when the member is moved into a certain one of its positions of adjustment; and means intermediate said device

and said mechanism to prevent said device from being rendered effective by said means actuated by said member when said mechanism is in any total-taking position.

14. In a machine of the class described, the combination of a plurality of lines of totalizers; actuators for said totalizers; a plurality of amount-determining devices to control said actuators; transfer means for each totalizer line and intermediate the denominational orders of the totalizers; mechanism having an add position, sub-total taking positions and total-taking positions to control the machine for adding, sub-total and total-taking operations; a device associated with the transfer means of a certain denominational order of the totalizer on one of said totalizer lines, and adapted to trip said transfer means to cause the adjacent higher order wheels of said totalizer on said one line to add 1 each operation, said device being normally held in an ineffective position; a lever common to all totalizer lines and actuated by said device to control the corresponding order of transfer means on the remaining totalizer lines; manipulative means adapted to be moved into a plurality of positions of adjustment; means actuated by said manipulative means to render said device effective when said manipulative means is moved into a certain position of adjustment; and means connected to said device and controlled by said mechanism when said mechanism is in any position away from its add position to supersede the control of said device by said means actuated by said manipulative means, by preventing said device from being rendered effective under control of said last mentioned means.

15. In a machine of the class described, the combination of a plurality of totalizers; actuators for said totalizers; a plurality of amount determining devices to control said actuators; transfer means for each totalizer and intermediate the denominational orders of the totalizers, said transfer means adapted to be tripped by the next lower order wheels to cause a carry to the adjacent higher order wheels; mechanism having an add position, sub-total taking positions, and total-taking positions to control the machine for adding, sub-total and total-taking operations; a device common to the transfer means of a certain denominational order of all totalizers, and adapted to trip all of said transfer means simultaneously to cause the adjacent higher order wheels of said totalizers to add 1 on each operation of the machine, said device being normally held in an ineffective position; manipulative means adapted to be moved into a plurality of positions of adjustment; means actuated by said manipulative means to render said device effective when said manipulative means is moved into a certain position of adjustment; and means connected to said device and controlled by said mechanism when said mechanism is in any position away from its add position to supersede the control of said device by said means actuated by said manipulative means, by preventing said device from being rendered effective under control of said means which is actuated by the manipulative means.

16. In a machine of the class described, a combination of a plurality of totalizers; actuators for said totalizers; a plurality of amount determining devices to control said actuators; transfer means for each of said totalizers and intermediate the denominational orders of the

totalizers, said transfer means adapted to be tripped by the next lower order wheels to cause a carry to the adjacent higher order wheels; mechanism having an add position, sub-total-taking positions and total-taking positions to control the machine for add, sub-total and total-taking operations; a device associated with the transfer means of a certain denominational order of one of said totalizers, and adapted to trip said transfer means of said certain order to cause the adjacent higher order wheel of said one totalizer to add 1 each operation of the machine, said device being normally held in an ineffective position; a second device adapted to be actuated by the first device to trip the transfer means corresponding to said certain denominational order of the remaining plurality of totalizers when said first device is rendered effective; manipulative means adapted to be moved into a plurality of positions of adjustment; means actuated by said manipulative means to render said first device effective when said manipulative means is moved into a certain position of adjustment; and means connected to said first device and controlled by said mechanism when said mechanism is in any position away from its add position to supersede the control of said first device by said means actuated by said manipulative means, by preventing said first device from being rendered effective under control of the means which is actuated by said manipulative means.

17. In a machine of the class described, the combination of a plurality of lines of totalizers; actuators for said totalizers; a plurality of amount-determining devices to control said actuators; transfer means intermediate the denominational orders of the totalizers, said transfer means adapted to be tripped by the next lower order wheels to cause a carry to the adjacent higher order wheels when said lower order wheels 40

pass from 9 to 0; means common to the transfer means of all of said lines of totalizers to restore all tripped transfer means to normal positions; devices cooperating with and adapted to be actuated by a certain plurality of said restoring means in the corresponding denominational orders to set said devices in positions to lock the associated transfer means in untripped positions; retaining means for each of said devices to retain the latter in said set positions; differentially adjustable means cooperating with said retaining devices; and a member adapted to be moved into a plurality of different positions to cause said adjustable means to control certain of the retaining means to retain their associated devices in effective positions when said member is moved into one of its positions of adjustment, and to cause said adjustable means to control certain other of said retaining means to retain their associated devices in effective positions when said member is moved into another of its positions of adjustment.
